BY

Alexander Sawill
ATTORNEYS

UNITED STATES PATENT OFFICE.

NORMAN G. BAKER, OF MUSCATINE, IOWA.

WHISTLE.

Application filed November 6, 1922. Serial No. 599,467.

To all whom it may concern:

Be it known that I, NORMAN G. BAKER, a citizen of the United States, residing at Muscatine, in the county of Muscatine and State of Iowa, have invented certain new and useful Improvements in Whistles; and I hereby declare that the following is a full, clear, and exact description thereof, reference being had to the accompanying drawings, which form part of this specification.

This invention is a novel improvement in whistles for musical instruments, such as calliopes. The object of the present invention is to insure more direct and uniform pressure of the air discharged from the cup of the whistle; and to improve the construction of the air distributing devices in the cup of the whistle.

I will explain the invention with reference to the accompanying drawings and summarize in the claims the novel features for which protection is desired.

In the drawings:

Fig. 1 is an enlarged vertical section through the complete whistle.

Fig. 2 is a transverse section on the line 2—2 Fig. 1, looking downwardly.

Fig. 3 is a detail section on the line 3—3 Fig. 2.

Fig. 4 is a perspective of the cup and bell supporting devices thereon detached.

Calliope whistles are usually made with a hollow top piece called a bell and a lower part called a cup, which are disposed in axial alinement, with the bell spaced from the cup, the distance therebetween regulating the tone or speaking quality of the whistle. The bell is made adjustable toward or from the cup, and supported thereon. Within the cup is an air distributing disk by which the air or steam is distributed below the open end of the bell to produce the sound. The cup is made fast to a suitable support and connected with a compressed air or steam supply, or to the exhaust of a combustion engine.

In the accompanying drawings the cup 1 is closed at or near its bottom by a plate 1^a, and near its top by a plate 1^b. These plates have axial openings. Between plates 1^a, 1^b is interposed a tube 1^c arranged axially of the cup and communicating at its ends with the axial openings in said plates. These parts 1^a, 1^b, 1^c may be soldered together or otherwise suitably connected. The plate 1^a

may be provided with a thickened portion 1^e adjacent the lower end of tube 1^c, which portion 1^e may be formed integral with or separate from plate 1^a; or the tube. This portion 1^e is internally threaded for engagement with a threaded nipple 8 which may be attached to a support 9 of any suitable kind. The nipple 8 may be connected by a pipe 8^a with a compressed air or steam supply.

Within the cup 1 and supported on the top plate 1^b is a spreader disk 2, the top of which should be about flush with the top edge of the cup 1, and this disk should be of an exterior diameter slightly less than the interior diameter of the cup 1, so that an air or steam escape passage P will be left between the edge of the plate and the inner wall of the cup 1. The spreader plate 2 is spaced from the top plate 1^b to form a small air distributing chamber C, which directly communicates with the interior of the tube 1^c, and is adapted to distribute the air or steam entering the tube 1^c to the outlet P without lessening the pressure of the air or steam. The spreader 2 is preferably stamped with depending lugs, 2^a, which lugs will support the spreader 2 on the plate 1^b and suitably space the spreader 2 from said plate. After the spreader is properly adjusted in the cup 1, so that the space P will be of uniform extent throughout, it may be secured by any suitable means. As shown, screws 3 are passed through holes 2^c in the spreader 2 and engage threaded apertures in the top plate 1^b. Preferably the holes 2^c are of larger diameter than the shanks of the screws 3 so that after the spreader is placed on the plate 1^b it can be adjusted laterally on this plate until the passage P is uniform throughout, then the screws 3 can be tightened, thereby binding the spreader 2 securely in position. The openings might be formed within the lugs 2^a, so that the screws will pass through the spacing lugs. The lugs 2^a might be used as means for fastening the disk by dropping solder into these hollow lugs, after the spreader is properly positioned, thereby securely attaching same to the top plate, also for regulating distance between 2 and 1^b.

Supported on and attached to the cup 1 is an internally threaded annulus 4 which is connected to the cup by vertically disposed bars 4^a attached to the outer side of the

annulus and soldered or otherwise secured to the outer side of cup 1, as shown in Figs. 1 and 4.

The bell 5 is usually formed of a pipe 5 closed at its upper end and externally threaded to engage the annulus, 4 and it can be adjusted until the lower end of the bell is the desired distance from the upper end of the cup, or the air passage P, and when 10 so adjusted the bell can be secured by means of a set screw 4^c, tapped through the annulus 4, as indicated in Fig. 4. The tone of the whistle can be regulated by means of an adjustable plunger 6 arranged in the bell 15 threaded for exact adjustment with inset holes to engage wrench for adjusting in the usual manner.

Whistles have heretofore been made with a cup such as 1, and an annular opening 20 such as P in its upper end, and the air was discharged directly into the bottom of the cup, and could expand in the cup below the spreader and between the nipple 8 and the outlet passage P, and thus the pressure of 25 the air at its entry into the cup and at the outlet therefrom would be varied or irregular. I prevent expansion of the air in the cup below the passage P by confining the air in the cup to the small tube 1^c, which is 30 tapered with nozzle effect to give pressure right at opening at any crack, which is very much less in diameter than the cup, and the air passes from the tube 1^c to the distributing chamber C and thence directly to the 35 opening P in my invention, and thus the air or steam from the pipe 8^a is transmitted without any expansion or diminution of pressure in the cup directly to the outlet P, and the air pressure is maintained at the 40 passage P. But for the tube 1^c the air from the nipple 8 would expand and fill the entire cup before reaching the passage P, and the pressure would be lessened, and the tone would be correspondingly affected; this 45 would be most noticeable when the instrument was playing short staccato notes.

The spreader 2 can be very accurately positioned on the plate 1^b so that it will be truly centered within the cup 1, and when 50 positioned can be secured by the screws 3, or solder, or both, as described. After the spreader 2 is properly positioned and secured to the plate 1^b, the cup 1 is attached to the air supply nipple 8, and the bell 5 properly adjusted and secured. When air 55 is admitted to the nipple 8 it flows directly without expansion through the tube 1^c to chamber C and thence to the passage P escaping between the cup and the lower end of 60 the bell and causing the bell to sound.

In my whistle the air or steam is confined to a small passage within the cup so that its pressure is maintained approximately the same when it reaches the air outlet P as it 65 does in the supply pipe 8^a, as the large space

in the cup exterior to the tube 1^c and around the plates 1^a, 1^b, is closed and the air is not admitted thereto, and does not have to traverse the same in passing from pipe 8^a to the outlet P.

What I claim is:

1. A whistle having a cup and a bell; upper and lower plates in the cup, each having an opening; a tube between the plates connecting with said openings; and means for connecting the lower end of the tube with an air or steam supply; a spreader in the upper end of the cup supported on and spaced from the upper plate to disseminate air or steam passing through the tube between the spreader and the upper plate; and means for securing the spreader in position. 70

2. A whistle having a cup and a bell; upper and lower plates in the cup, each having an opening; a tube between the plates connecting with said openings, and means for connecting the lower end of the tube with an air or steam supply; a spreader in the upper end of the cup having lugs to support same on and space it from the upper plate to disseminate air or steam passing through the tube between the spreader and the upper plate, and means for securing the spreader in position. 80

3. A whistle having a cup and a bell; upper and lower plates within the cup, each having an opening; a tube between the plates connecting with said openings; a spreader in the upper end of the cup and supported on and spaced from the upper plate in the cup to disseminate air or steam passing through the tube between the spreader and the upper plate, said spreader having openings for the passage of retaining screws; screws passing through the opening in the spreader and engaging the upper plate to fasten the spreader thereon, said openings being slightly larger in diameter than the shanks of the screws, substantially as described. 90

4. A whistle having a cup and a bell; upper and lower plates in the cup, each having an opening, a tube between the plates connecting with said openings; means for connecting the lower end of the tube with an air or steam supply; a spreader in the upper end of the cup having lugs formed thereon to support same on and space it from the upper plate to disseminate air or steam passing through the tube between the spreader and the upper plate; said spreader having openings for the passage of retaining screws; and screws passing through the openings in the spreader and engaging the upper plate to fasten the spreader thereon, substantially as described. 100

In testimony that I claim the foregoing as my own, I affix my signature.

NORMAN G. BAKER.
